CLAIM

The ornamental design for a filled dough product, as shown and described.

DESCRIPTION

FIG. 1 is a top perspective view of a filled dough product of the present invention;

FIG. 2 is a top view of the filled donut product of FIG. 1;
FIG. 3 is a bottom view of the filled donut product of FIG. 1;

FIG. 4 is a side view of the filled donut product of FIG. 1;
FIG. 5 is an end elevational view of the filled dough product of FIG. 1;

FIG. 6 is an end elevational view of the filled dough product of FIG. 1; and,

FIG. 7 is a cross-sectional view of the filled dough product of FIG. 1 taken along line 7-7 in FIG. 4.

The broken lines in FIGS. 1-5 illustrate portions of the filled dough product that form no part of the claimed design.

1 Claim, 3 Drawing Sheets
